Des. 198,580
Patented July 7, 1964

198,580

COMBINED MEASURING, MOLDING AND CUTTING TOOL

James B. Swett, Barrington, and Henry J. Marien, Warwick, R.I., assignors to Rexall Drug and Chemical Company, Los Angeles, Calif., a corporation of Delaware

Filed Mar 5, 1964, Ser. No. 78,881

Term of patent 14 years

(Cl. D44—29)

FIG. 1

FIG. 2

FIG. 5

FIG. 3

FIG. 4

FIG. 6

FIGURE 1 is a perspective view of a combined measuring, molding and cutting tool showing our new design;
FIGURE 2 is a top plan view thereof;

FIGURE 3 is a cross section taken on line 3-3 of FIGURE 2;

FIGURE 4 is a bottom plan view thereof;

FIGURE 5 is a fragmentary sectional view taken on line 5-5 of FIGURE 2;

FIGURE 6 is a fragmentary sectional view taken on line 6-6 of FIGURE 4;

This application is a continuation-in-part of our earlier application Serial No. D. 74,616, filed April 25, 1963, and now abandoned.

We claim:

The ornamental design for a combined measuring, molding and cutting tool, as shown and described.
